Primary Examiner — Marianne Pandozzi*Assistant Examiner* — Jae Liang*(74) Attorney, Agent, or Firm* — Polsinelli PC(57) **CLAIM**

The ornamental design for a lid and bottle combination, as shown and described.

DESCRIPTION

FIG. 1 is a top perspective view of a lid and bottle combination showing our new design;

FIG. 2 is a front view of the lid and bottle combination;

FIG. 3 is a rear view of the lid and bottle combination;

FIG. 4 is a right side view of the lid and bottle combination;

FIG. 5 is a left side view of the lid and bottle combination;

FIG. 6 is a top view of the lid and bottle combination;

FIG. 7 is a bottom view of the lid and bottle combination; and,

FIG. 8 is a top perspective view of the lid and bottle combination with the lid in its open position.

The broken lines in the drawing depict portions of the lid and bottle combination that form no part of the claimed design.
